SPRING MATTRESS CORNER BRACKET OR
CORNER BLOCK

Walter P. Gisske, Chicago, Ill., assignor to
Wrought Washer Mfg. Co., Milwaukee, Wis., a
corporation of Wisconsin

Application June 15, 1938, Serial No. 213,761

1 Claim. (Cl. 5—206)

My invention relates to improvements in a
spring mattress corner bracket or corner block.

The object of my invention is to provide a
spring mattress corner bracket so shaped and
provided with suitable strengthening means that
it may be made as a metal stamping, and still
provide adequate strength to meet the extreme
stresses placed upon such a bracket.

Another object of my invention is to provide
a spring mattress corner bracket made of one
piece of drawn metal whereby to provide one
integral box-like structure having great strength.

In the drawing:

Figure 1 is a perspective of my corner bracket
installed in a somewhat conventional type of
spring mattress and disclosing the corner of such
a mattress and the corner of a metal bed frame
in conjunction with which my corner bracket
may be used.

Figure 2 is an elevation of my corner bracket
and the portion of a cross bar of a spring mat-
tress thereupon.

Figure 3 is a plan view of my corner bracket.

Figure 4 is a vertical section on line 4—4 of
Figure 2 and showing a portion of a stretcher
bar in position in the lower end of my corner
bracket.

Figure 5 is a section on line 5—5 of Figure 4.

Figure 6 is a section on line 6—6 of Figure 4.
Figure 7 is a side elevation of a portion of a
bed frame and a mattress showing my corner
brackets.

Like parts are designated by the same reference
characters throughout the several views.

In the usual bed construction, a corner post
10 is spaced and braced from the other corner
posts by a longitudinal "rail" 11 and by a head
bar 12. A spring mattress, indicated generally
at 13, includes a longitudinal stretcher bar 14
and a cross bar 15, the cross bar 15 being off-set
upwardly from the stretcher bar 14. Between the
cross bars 15 a spring mattress 16 is stretched
and kept under tension by suitable springs 17
which are hooked between the mattress and the
cross bars, as indicated most clearly in Figure 1.
The mattress 16 is thus supported at some dis-
tance above the rail 11 and the stretcher bar
14 to provide for free spring action of the mat-
tress without danger that it will impinge upon
any members which might obstruct the spring
action.

My corner bracket 20 supports the cross bar
15 in proper relation to the stretcher bar 14, and
at the same time provides a foot 21 to rest upon

the rail 11 and thus support the entire mattress
structure 13.

Many forms of corner brackets 20 have hereto-
fore been provided, but attempts to provide a suc-
cessful bracket in the form of a metal stamping 5
have not been successful in part because of the
terrific strains which are placed upon the bracket
because of the tendency to distortion exerted by
the springs 17 and by the weight of any object
upon the mattress 16 tending to wrest the bracket 10
from its connection with the stretcher bar 14.

I have provided in my bracket 20 elements of
extreme structural strength which meet the prob-
lems which have heretofore discouraged the use
of pressed metal brackets. 15

My bracket 20 is in general a box shaped metal
stamping including a back wall 22, side walls
23 and 24, and end walls hereinafter described.
At the upper end of the box a portion of the back
wall 22 is inclined, as shown at 25, and the upper 20
end of the back wall 22 is bent inwardly in an
end wall 26 to provide a cross bar seat for the
cross bar 15 which is secured in position by rivets
27, as shown in Figures 2 and 4. This end wall
26, being drawn into its position from the mate- 25
rial of the back and side walls lends extreme
strength to the bracket structure. To increase
the lateral stability of the box I turn the side
walls outwardly at 28.

At the lower end of the box I provide side wall 30
extensions 30 and 31 which comprise extensions
of unequal length. Extension 30 is corrugated,
as shown at 32, and is bent to dispose the ex-
tension 30 across the face of the channel, and to
extend therebeyond to form a part of the foot 35
21. The extension 31 is bent outwardly and
parallel to extension 30 to reinforce extension 30
and to provide increased strength as a part of
foot 21. The portions of the extensions 30 and
31 which lie parallel to one another may be spot 40
welded or otherwise secured together to increase
their stability as a "foot" which may rest on the
rail 11. By thus securing the extensions 30 and
31 together, I also brace one side wall of the box
with reference to the other. 45

The lower end of the back wall 22 is shaped as
shown most clearly in Figure 4 to provide a shelf
35 and a seat at 36. The lower margin of the
extension 32 is shaped as shown most clearly in
Figure 2 to receive stretcher bar 14, which con-
sists of an ovoid tubular member against which
the curved surface 34 of the extension 32 may
abut and into the shelf of which 35 it may extend,
35 also preventing the ovoid tube from turning 55

and thus securing a rigid total assembly. The seat 36, referred to above, is in reality an end of the box since it is drawn from the side walls and from the back wall 22. Thus in forming the seat 5 for the stretcher bar 14 there is added strength which I provide in a curved end wall of the box.

At spaced points in the back corners of the box, and extending somewhat into the back wall and into the side walls thereof, I provide ribs 37 10] to increase the shape holding strength of the bracket 20. Ribs 38, to strengthen the back wall 22 of my bracket are also provided as shown most clearly in Figures 2, 5 and 6.

No particular means for securing stretcher bar 15 14 in position upon the seat 36 and upon shelf 35 is required since the centripetal pull of the springs 17, and any weight upon the mattress 16, will tend to draw the bracket "inwardly." However, if desired, the lip 36 and the stretcher bar 20 14 may be welded or otherwise secured together at 39.

From the above description it will be seen that I have provided in a stamped metal corner bracket tremendous strength to withstand the great 25 strains thrown upon a structure of this kind. The cross bars 15 and stretcher bar 14 are adequately supported from and by one another, and by reason of the provision of the various parts, as described, each element is strengthened in a 30 manner not heretofore possible in the construction of corner brackets. At the same time I

have provided a product which is light in weight, having a cost of manufacture lower than previously used brackets, and having rigidly actually greater than of malleable castings heretofore used.

Much of the strength which I have provided in my new corner bracket or corner "block" is obtained by drawing the ends of the walls and the bottom of the "box" into an end wall integrally and the integral drawn metal, even though light 10 in cross-section, lends tremendous strength to my completed product.

I claim:

A spring mattress corner bracket having a stretcher bar and a cross bar, said bracket comprising a generally box shaped stamping having a channel portion, the lower end of which has side wall extensions of unequal length, the longer of said side wall extensions being formed across the face of the box and extended therebeyond, 20 the shorter of said extensions being extended parallel to and secured to the longer extension beyond the box wall whereby to reinforce the longer side wall extension and provide a foot, the portion of the longer side wall extension extending 25 across the face of the box being cut away to provide an edge to abut the stretcher bar, the end of which is received in the box, and a lip extension of the lower end of the channel being in-turned to provide a seat for said stretcher bar. 30

WALTER P. GISSKE.
